UNITED STATES PATENT OFFICE.

LAWRENCE R. JONES, OF WHEATON, ILLINOIS.

LOW-WATER-ALARM DEVICE FOR BOILERS.

1,110,442.

Specification of Letters Patent. Patented Sept. 15, 1914.

Application filed June 14, 1913. Serial No. 773,622.

To all whom it may concern:

Be it known that I, LAWRENCE R. JONES, a citizen of the United States, residing at Wheaton, in the county of DuPage and 5 State of Illinois, have invented certain new and useful Improvements in Low-Water-Alarm Devices for Boilers, of which the following is a specification.

My invention relates to low water alarm devices for boilers and has for its general object to provide such a device in which the fusible element, when destroyed in the course of the functional operation of the device, may readily be renewed from the outside 10 of the boiler without permitting needless escape of steam and without putting the boiler out of commission.

In the drawing wherein I have shown a single embodiment of my invention, for purposes of illustration: Figure 1 is a central vertical section through the alarm; Fig. 2 is a transverse section on line 2—2 of Fig. 1. Fig. 3 is a transverse section on line 3—3 of Fig. 1. Fig. 4 is a detail section on line 25 4—4 of Fig. 1.

In the drawing 10 indicates a fragment of the boiler shell having an opening 10' therein through which is screwed from the inside of the boiler a slender bushing 11, 30 flared as at 12 at its lower end and having threaded therein a tubular casing 13. At its bottom, at the desired elevation in the boiler, said casing carries one element of a valve. The valve is herein shown as of turn-cock construction, and its ported shell or casing member 14 has its flared rim 15 screwed onto a sleeve 16 which is screwed onto the extremity of the tubular casing 13, said sleeve 16 having a reduced rim alining 35 with the tube to form a shoulder 17. Screws 18 and 19 fix the shell 14 on sleeve 16, and the sleeve on tube 13. Within the shell 14 interfits the taper valve 21 having its ports leading into a central chamber 22, rotation 40 of the valve obviously permitting or preventing communication between the interior chamber and the boiler space. The valve underlies the sleeve 16, and is adjustable in its shell to take up wear by the usual threaded stem 24 passing through the bottom of 45 the shell and carrying nuts 25. The bottom of the chamber has therein an apex, 26, so that the bottom walls of the valve chamber slope toward the valves.

50 While I have thus described for purposes of full disclosure one specific form of valve

suitable for employment in the practice of my invention; other forms of valve may be employed.

The valve for controlling communication 60 between the interior and exterior of the tubular casing 13 is operated by a valve stem 27 which extends upward through the casing 13 and bushing 11 and carries, adjacent to its upper end, a turning handle 28. The 65 stem 27 is made hollow and is screwed and keyed, as at 29 to the throat of valve 21, so that the hollow stem opens into the interior chamber of the valve. The bushing 11 carries, outside of the boiler shell 10, a suitable 70 gland 30 for tightly packing the valve stem, and on said bushing may be mounted a bar 31 to which handle 28 may be padlocked.

Within the area of the casing 13 controlled by the valve, (so that fluid may be 75 admitted thereto from the boiler, or excluded therefrom, by operation of the valve) I arrange the removable, fusible element which controls a passage, normally closed by the fusible element, and opened to the egress 80 of steam when said member fuses. In the specific construction shown an alarm tube 33 is fitted snugly within the hollow valve stem 27, so that its lower end may protrude into the interior chamber of the hollow 85 valve, the lower end of said tube being interiorly screw threaded to receive the threaded extremity of the fusible plug 35, made of any metallic alloy adapted to fuse at the desired temperature. For preventing escape 90 of steam or water between the alarm tube 33 and the surrounding valve stem, and anchoring the tube in proper position I provide on the extremity of the valve stem, above the handle 28, a threaded cap 36 coating with 95 a flange 37 fast on tube 33 and positioning a packing ring 38 interposed between said flange and the end of stem 27 to pack the joint with the alarm tube and the end of the valve stem.

In the operation of the device the fusible plug 35 is located below the normal water line of the boiler and the valve is open. Should the water in the boiler get too low, so that the plug may be attacked by the 105 steam, the plug fuses and the escape of steam through the alarm tube, (or the operation of any suitable device worked by steam so escaping,) gives the alarm. The fused metal runs out of the valve by reason 110 of its angular bottom wall. Thereupon the valve 21 controlling communication between

the interior of the boiler and the interior of the casing 13 may be closed, so cutting off the escape of steam, and then the alarm tube may be removed from its position and 5 a new fusible element inserted in its extremity and the alarm tube again inserted in place, after which the valve may again be opened to restore all of the parts to normal condition.

10 While I have herein described in some detail a particular embodiment of my invention, it will be apparent to those skilled in the art that many changes might be made in the details of constructions without departure from the spirit of my invention and 15 within the scope of the appended claims.

Having described my invention, what I claim is:

1. In a boiler alarm device, the combination of a casing extending into the boiler to 20 a point below the normal water level and communicating with the exterior through a single opening in the boiler shell, a valve within the boiler for opening and closing 25 communication between the interior of said casing and the interior of the boiler, means extending longitudinally through said casing for operating the valve and a fusible member located within the casing and removable therefrom through the casing.

2. In a low water alarm of the character described, the combination with the boiler shell, of a casing supported by such shell and extending into the boiler below the normal 35 water level, a valve controlling communication between the interior of said casing and the interior of the boiler, a valve stem extending through said casing to the exterior thereof, an alarm tube extending to 40 a point within the casing and removable therethrough, and a fusible element, located below the normal water level, normally closing said alarm tube.

3. In a low water alarm of the character described, the combination of a casing adapted 45 to be secured to the shell of a boiler, a valve at one extremity of said casing, controlling the communication of the interior of said casing with the interior of the boiler, a hollow valve stem extending through said casing to the exterior thereof, a removable alarm tube extending through the hollow valve stem, a fusible member normally closing the inner end of said alarm tube and 50 positioned within said casing, whereby the opening and closing of the valve controls the communication of the boiler-contained fluid with the fusible member.

4. In a device of the character described, 60 the combination of a tubular casing, a valve casing carried by the lower end thereof, a hollow valve within said casing, a valve stem extending through said casing, a tube extending through said hollow valve stem 65 and at its lower end entering the hollow

valve, a fusible plug normally closing the lower end of said tube, a bushing adapted to engage the shell of a boiler surrounding said valve stem and engaging the casing to carry the same, packing means between the bushing and valve stem, a valve handle carried by said stem, and packing means between the alarm tube and the hollow valve stem. 70

5. In a low water alarm of the character described, the combination of a valve positioned within the shell of a boiler, a hollow valve stem extending through said shell to the exterior thereof, a removable alarm tube extending through the hollow valve stem, a fusible member normally closing the inner end of the alarm tube and positioned 75 within the valve, whereby the opening and closing of the valve controls the communication of the boiler contained fluid with the fusible member. 80

6. In a low water alarm of the character described, the combination of a valve casing secured within the interior of the shell of a boiler, a hollow valve seated within the said valve casing, a hollow valve stem extending 90 through the boiler shell to the exterior thereof, a removable alarm tube extending through the hollow valve stem, a fusible member normally closing the inner end of the said alarm tube and positioned within the 95 hollow valve, whereby the opening and closing of the valve controls the communication of the boiler contained fluid with the fusible member.

7. In a low water alarm of the character described, the combination of a valve casing positioned within the shell of the boiler, a hollow valve seated within the casing, a hollow valve stem extending through the shell to the exterior thereof, a removable 100 alarm tube extending through the hollow valve stem, a fusible member normally closing the inner end of the alarm tube and positioned within the valve, the lower faces of 105 the apertures in the said valve members being tapered downward from a point beneath the fusible plug to the outer openings substantially as and for the purpose set forth. 110

8. In a low water alarm valve of the character described, the combination of a valve casing, a hollow valve within the casing, a hollow valve stem extending to the exterior of the boiler, a removable alarm tube within the hollow valve stem, and a removable fusible member normally closing the inner end of the alarm tube and positioned within the hollow valve, the lower walls of the valve passages being tapered away from a point beneath the fusible plug to permit the gravitational flow of the fused plug away from the valve parts and prevent their obstruction. 115 120

9. In a low water alarm, the combination of a valve positioned within the shell of a 125 130

boiler, a hollow valve stem extending through said shell to the exterior thereof, a removable alarm device extending through the hollow valve stem, and a fusible member carried at the inner end of the alarm device, whereby the opening and closing of the valve controls the communication of the boiler contained fluid with the fusible member.

10. In a low water alarm of the character described, a casing adapted to be secured to the shell of a boiler, a valve at the extremity of said casing, controlling the communication of the interior of said casing with the interior of the boiler, means extending 15 through said casing to the exterior thereof,

for operating the said valve, a removable alarm device extending through the said casing, a fusible member, carried at the inner ends of the said alarm device and positioned within said casing, whereby the opening and 20 closing of the valve controls the communication of the boiler contained fluid with the fusible member.

In testimony whereof I hereunto set my hand in the presence of two witnesses.

LAWRENCE R. JONES.
